US00D913777S

(12) United States Design Patent (10) Patent No.: US D913,777 S
(45) Date of Patent: * Mar. 23, 2021

(54) STRETCHABLE HANGER

(71) Applicant: Haoliang Liu, Shenzhen (CN)

(72) Inventor: Haoliang Liu, Shenzhen (CN)

() Term: 15 Years

(21) Appl. No.: 29/680,761

(22) Filed: Feb. 19, 2019

(51) LOC (13) Cl. 08-05

(52) U.S. Cl.

USPC D8/370

(58) Field of Classification Search
